UNITED STATES PATENT OFFICE.

DANIEL E. HALL, OF SOMERVILLE, MASSACHUSETTS.

STEERING APPARATUS.

SPECIFICATION forming part of Letters Patent No. 761,223, dated May 31, 1904.

Application filed September 23, 1903. Serial No. 174,264. (No model.)

To all whom it may concern:

Be it known that I, DANIEL E. HALL, a citizen of the United States, residing at Somerville, in the county of Middlesex and State of Massachusetts, have invented an Improvement in Steering Devices, of which the following description, in connection with the accompanying drawings, is a specification, like letters on the drawings representing like parts.

10 My invention is an improvement in steering mechanism for motor-carriages and the like. The high speed and severe usage of present-day motor-carriages test to the utmost the strength, compactness, and permanence of adjustment of all parts of the machine, so that inventors are now exerting themselves toward improving the various parts of the machine in these respects, my invention relating to the steering mechanism, the objects thereof being 15 to provide the simplest construction and fewest number of parts arranged to be quickly put in place, readily disconnected, easily disassembled, maintained at all times compact, noiseless, certain, and instant in movement, (there being no backlash or lost motion,) all 20 the parts also being entirely adjustable to wear, the construction offering a braced resistance in all directions of strain.

I employ a screw-movement for certainty of 25 action and yet arranged in such a manner as to give full steering movement with slight motion, permitting the use of either a hand-wheel or lever, and also my construction permits mounting the apparatus either on the vehicle-body or the running-gear, and any portion thereof may be removed for inspection or repair without disturbing the rest.

The constructional details and further advantages of my invention will be pointed out 30 in the course of the following description, reference being had to the accompanying drawings, in which I have shown a preferred embodiment of the invention, and later will be more particularly defined in the appended 35 claims.

In the drawings, Figure 1 represents in side elevation, partly broken away, a portion of a vehicle provided with one embodiment of my improvement and illustrates one position of 40 mounting the same. Fig. 2 is an enlarged de-

tail in vertical section and partly broken away, showing the lower operating portion of the device. Fig. 3 is a transverse sectional view thereof, partly broken away, taken on the dotted line 3 3, Fig. 2. Figs. 4 and 5 are views 55 similar to Figs. 2 and 3, showing a modified construction.

For purposes of illustration I have shown my invention applied to a motor-car in which the steering-gear is connected to an arm *a*, 60 projecting from a knuckle *a'*, adjacent the front wheel *a''* of the vehicle. From said arm *a* extends a rod *b*, provided at its rear end with a ball *b'*, held in a socket formed partly in a cap-plate *b''* and an arm *b''*, the two being 65 held together by bolts *b'''*, as clearly shown in Fig. 2.

The arm *b''* is freely pivoted in a hanger *b''*, supported by a bracket *b''* on the vehicle and carrying a steering-column *b''* and connected 70 mechanism. The hanger *b''* is of especially strong construction, having opposite pairs of arms *b''* *b''* extending upwardly to longitudinal journal-bearings *b''* *b''* and provided at their lower part with transverse journal-bearings 75 *b''* *b''*.

In the bearings *b''* *b''* is mounted a shaft *b''*, provided with a quick-motion screw or threaded hub *b''* (herein shown as a three-screw single-turn screw) for strength and quickness of motion, and about this hub *b''* is a threaded sleeve *b''*, having an ear *b''* extending downwardly therefrom between ears or wings *b''*, projecting upwardly from a hub *b''*, provided on the upper end of the arm *b''*.

The ear *b''* has a square aperture *b''*, in which is seated a split slide-block *b''*, made up of two parts split lengthwise, as clearly shown in Fig. 2, and being formed at its opposite sides to receive opposite conical sleeves or tightening-cones *b''*, (see Fig. 3,) movable longitudinally toward each other on a bolt *b''* and supported in the ears or wings *b''*. The hole *b''* is longer than the block *b''*, so that the latter can move freely lengthwise therein.

In Fig. 3 I have shown opposite oil-holes *b''*. The hub *b''* is similarly mounted between the hanger-arms *b''* *b''*, being supported on a bolt *b''*, carrying conical sleeves or bearings *b''*, journaled at *b''* *b''*, respectively, in the 100

hanger and engaging at their conical ends correspondingly-shaped seats b^{29} , formed in the hub b^{21} .

From the foregoing description it will be seen that when the column b^7 is turned the sleeve b^{18} will thereby travel longitudinally on the shaft b^{16} and rock the arm b^3 on its pivots b^{28} in the hanger b^5 , thereby moving the rod b longitudinally one way or the other and correspondingly steering the vehicle.

As already intimated, it is of vital importance in this class of mechanism that it should be maintained noiseless and also that no looseness of parts or lost motion should be permitted, and accordingly my entire construction is devised with this end in view.

The block b^{23} is adjusted so as to move freely longitudinally but have no lateral movement, all wear being taken up simply by adjusting the tightening-cones slightly toward each other. By this means the most delicate adjustment is possible, so that the requisite free upward and downward movement of the block b^{23} may take place without any possibility of looseness, lost motion, or rattling.

The lower end of the shaft b^{16} is rounded, as indicated at b^{30} , and seats against an end-thrust bearing b^{31} , held in the bearing b^{12} and adjusted by a bolt b^{32} , a shoulder b^{33} being provided on said shaft for engaging the inner side of the bearing b^{13} .

The sleeve b^{18} is shown as split, Fig. 3, and its free ends b^{34} b^{35} are clamped together by a bolt b^{36} and lock-nut b^{37} .

35 The column b^7 is connected with the shaft b^{16} by a sleeve b^{38} , the latter being provided with a recess b^{39} , fitting the lower end of said column, and another recess b^{40} , fitting said shaft, so that the parts may be assembled, 40 as shown in Fig. 2, and connected by tapered pins b^{41} b^{42} and threaded nuts b^{43} .

The journal-bearings b^{14} b^{15} extend beyond the arms of the hangers slightly, as indicated at b^{44} , and are preferably turned round, 45 as shown, and beneath the same project lugs b^{45} , apertured at b^{46} for the purpose of giving a rigid and strong bracket connection, the bracket b^6 having its arms mounted on the projections b^{44} and connected by bolts b^{47} to 50 the lugs b^{45} , the other end of the bracket being bolted in place on the vehicle body or reach or frame or wherever convenient.

55 The arm b^3 should normally occupy a substantially vertical position, as shown in Fig. 1; but it is desirable that the column b^7 may occupy a more or less inclined position or a vertical position, according to the kind of vehicle-body and preferences of the user, and accordingly the bracket b^6 has a series of 60 holes b^{48} , as shown clearly in Fig. 1, to permit the angle of the hanger b^5 and column b^7 to be changed, and the arm b^3 is made in two parts b^{49} b^{50} , the former having a series of holes and the latter a coöperating pin and 65 hole, the latter to receive a securing-bolt b^{51}

and the pin to enter the lower series of holes in the part b^{49} .

In Figs. 4 and 5 I have shown a modification of the longitudinal movable connecting means between the arm b^3 and sleeve b^{18} , the ear b^{19} in this instance entering between ears or wings b^{52} of a Y-pin b^{54} , freely movable up and down in a cylindrical hole provided in a tightening-cup b^{55} , carried in the hub b^{56} of the arm b^3 .

75 The cup b^{55} is conical externally to fit snugly in a conical hole or seat b^{57} in the hub b^{56} , said cup being split longitudinally, as shown clearly at b^{58} , to permit the sides of the cup to be brought toward each other by downward movement thereof in the conical seat b^{57} . Any convenient means for accomplishing this downward movement may be provided, said cup being herein shown as having a threaded extension b^{59} at its lower end, on which is mounted a nut b^{60} , held against vertical movement by a set-screw b^{61} , operating in a groove b^{62} of said nut. This accomplishes the same delicate adjustment that is accomplished in the other construction by means of the split 85 block.

The hub b^{56} is provided against uneven or loose movement in very much the same way as the other construction, being mounted on opposite cones b^{63} , seated in the opposite ends 95 of said hub and moving freely in holes b^{64} in the journal-bearings of the hanger and being held in proper adjustment by set-screws b^{65} , working in nuts b^{66} , carried at the ends of said openings b^{64} . The ear b^{19} is similarly mounted 100 in the Y-shaped pin, being provided on its opposite sides with conical seats in which hollow cones or sleeves b^{67} engage, being held in adjustment by lock-nuts b^{68} at the opposite ends of the bolt b^{69} , passing through the cones, ear, 105 and Y-pin.

110 It will be understood that the two-piece adjustable arm b^3 may be applied to this modified construction and that both constructions are susceptible of wide variation in form, arrangement, and combination of parts without departing from the spirit and scope of my invention.

115 From the foregoing description it will be evident that great strength and precision of movement is secured, the turning of the column b^7 causing the screw b^{17} to rotate, thereby shifting the sleeve b^{18} and through the pivoted ear and sliding connection rocking the arm b^3 to the right or left and compelling the rod b 120 to move correspondingly.

125 By having the whole apparatus mounted on the bracket b^6 and a ball-and-socket connection with the rod b I provide for mounting the steering mechanism either on the rigid running-gear or on the yielding vehicle-body. Practically the entire mechanism is carried in the single hanger, and this hanger is so shaped and constructed that it gives a strong bracing resistance in every direction of strain brought 130

upon it by the operation of the moving parts. If the arm b^3 should break, it is simply necessary to disconnect it from the ear b^{19} and move out its pivots in order to replace a new arm:

5 If the block b^{23} or pin b^{21} should get injured, it also can readily be replaced without materially disturbing the rest of the mechanism, and so on with all the moving parts.

The entire mechanism is readily disconnected or attached to the vehicle, and all the parts are easily assembled and disassembled. No rattling or looseness can take place because each part liable thereto is provided with fine adjustment. No lost motion or backlash upon 15 turning the column or steering-rod in the hanger can take place because all the parts extending therefrom to the steering-knuckle are so constructed that each responds instantly to any movement in the adjacent part. This 20 is of special importance in this class of vehicles, as it insures the safety of and gives confidence to the user.

Having described my invention, what I claim as new, and desire to secure by Letters 25 Patent, is—

1. A steering device for motor-vehicles and the like, comprising a sleeve movable longitudinally thereon, a pivoted arm, means connected to the free end of said arm for connection with the running-gear of the vehicle, and a sliding pivot connection between said sleeve and arm comprising a longitudinally-slotted ear extending from one of said parts, a split block occupying said slot and pivoted 30 to the other of said parts, and expanding means for expanding said block within said slot to maintain a close fit in the latter.

2. A steering device for motor-vehicles and the like, comprising a shaft, a sleeve movable 40 longitudinally thereon, a pivoted arm, means connected with the free end of said arm for connection with the running-gear of the vehicle, a split-block connection between said sleeve and arm, pivoted to one and sliding in 45 a slot in the other, and expanding means, consisting of a bolt, a conical sleeve thereon, and a nut, for expanding said split block within said slot to maintain a close fit in the latter.

3. A steering device for motor-vehicles and the like, comprising a column, a hanger at the lower end thereof, an arm mounted on a pivot in said hanger, the pivot comprising a bolt carrying conical sleeves journaled in the hanger and engaging correspondingly-shaped seats in 55 the arm, mechanism carried by said hanger for swinging said arm by rotation of said column, and means connected to the free end of said arm for connecting with the running-gear of the vehicle.

60 4. A steering device for motor-vehicles and the like, comprising a threaded shaft, a steering-column, a sleeve provided with connect-

ing recesses of different diameters, one fitting and receiving said shaft and the other fitting and receiving said column, and independent 65 tightening means for retaining said parts and tightening said shaft and column toward each other in said sleeve, a threaded sleeve mounted on said threaded shaft, a pivoted arm, means connecting said threaded sleeve and arm for 70 rocking the latter by longitudinal movement of the threaded sleeve, and means for connecting said arm to the running-gear of the vehicle.

5. In a steering device for motor-vehicles and the like, a column, a hanger at the lower 75 end thereof, a pivoted arm, mechanism carried by said hanger for swinging said arm by rotation of said column, and means independent of said swinging movement for changing the angle of said arm with relation to said 80 column.

6. In a steering device for motor-vehicles and the like, a column, a hanger at the lower end thereof, a pivoted arm, mechanism carried by said hanger for swinging said arm by 85 rotation of said column, said arm being composed of two parts, one connected to the pivot thereof, and the other being laterally adjustable thereon.

7. In a steering device for motor-vehicles 90 and the like, a column, a hanger at the lower end thereof, a pivoted arm, mechanism carried by said hanger for swinging said arm by rotation of said column, a bracket for supporting said mechanism rigidly on the vehicle, 95 and adjusting means for changing the angular position of said hanger, column, and mechanism with relation to said bracket.

8. In a steering device for motor-vehicles and the like, a column, mechanism connected 100 therewith for producing longitudinal movement, a longitudinally-movable rod extending at an angle to said column, means for transmitting said longitudinal movement to said rod, a hanger to which all of said mechanism 105 is connected, and a single supporting means co-operating with said hanger in supporting said mechanism.

9. In a steering device for motor-vehicles and the like, a column, a hanger at the lower 110 end thereof, a pivoted arm, mechanism carried by said hanger for swinging said arm by rotation of said column, said hanger having lugs extending therefrom, and a bracket provided with securing means for engagement 115 with said lugs, and with means for embracing said hanger at its opposite pivots.

In testimony whereof I have signed my name to this specification in the presence of two subscribing witnesses.

DANIEL E. HALL
